UNITED STATES PATENT OFFICE.

ALFRED E. LYLE, OF ARMSTRONG, MISSOURI.

DESIGN FOR A WELL AND CISTERNS COVER.

51,704.

Specification for Design.

Patented Jan. 22, 1918.

Application filed September 1, 1915. Serial No. 48,558. Term of patent 14 years.

To all whom it may concern:

Be it known that I, ALFRED E. LYLE, a citizen of the United States, residing at Armstrong, in the county of Howard and State of Missouri, have invented a new, original, and ornamental Design for Well and Cistern Covers, of which the following is a specification, reference being had to the accompanying drawing, forming a part thereof.

The figure is a perspective view of the well and cistern cover.

The cover is circular in plan view.

I claim:

The ornamental design for a well and cistern cover, as shown.

A. E. LYLE.
